UNITED STATES PATENT OFFICE.

HUBERT J. LA JOIE, OF EAST ORANGE, NEW JERSEY, AND UBERT URQUHART AND FRANK POKORNY, OF NEW YORK, N. Y., ASSIGNORS TO AUTO PNEUMATIC ACTION COMPANY, A CORPORATION OF NEW YORK.

EXPRESSION-CONTROLLING MECHANISM FOR PNEUMATICALLY-OPERATED MUSICAL INSTRUMENTS.

Application filed October 31, 1921. Serial No. 511,711.

In a pneumatically operated player piano, the blow of the hammer is governed by the tension of the suction or exhaust applied to the particular pneumatic which operates such hammer and by regulating said tension the "expression," "touch," or "dynamic action" is controlled. By controlling this regulator automatically from the music sheet an accurate reproduction of an artist's playing can be obtained. An instrument working on this plan is known as a reproducing player piano.

The object of this invention is to provide a piano action of this type which can be easily and cheaply manufactured as a unit so that it can be quickly and expeditiously placed in position in the piano.

To this end, the invention consists of the mechanisms described in this specification and illustrated in the accompanying five sheets of drawings forming part of this application.

Referring to these drawings—

Fig. 1 is a front elevation of a reproducing player piano containing our improvements and illustrating in outline the principal mechanisms thereof;

Fig. 2 is a front elevation partly in section, illustrating one of the expression controlling units;

Fig. 3 is an end elevation thereof;

Fig. 4 is a cross-sectional plan thereof on the line 4—4 of Fig. 2;

Fig. 5 is a cross-sectional elevation thereof on the line 5—5 of Fig. 3;

Fig. 6 is an end elevation of the passage or duct board on which the expression pneumatic and the valve units therefor are mounted;

Fig. 7 is an end elevation of one of the valve units;

Fig. 8 is a cross-sectional view thereof on the line 8—8 of Fig. 7;

Fig. 9 is a cross-sectional elevation on the line 9—9 of Fig. 2, illustrating another of the valve units;

Fig. 10 is an end elevation of part of the passage or duct board, illustrating the way the valve unit shown in Fig. 9 is connected;

Fig. 11 is an elevation partly in section, illustrating the stop pneumatic and its controlling valve;

Fig. 12 is a cross-sectional plan taken on the line 12—12 of Fig. 11;

Fig. 13 is a diagram illustrating the connections between the tracker apertures and expression unit;

Fig. 14 is a front elevation on an enlarged scale of the spool box and its appurtenances;

Fig. 15 is a front elevation on an enlarged scale illustrating the cut-off and motor governor secured to the bottom of the key bed;

Fig. 16 is an end elevation thereof partly in section;

Fig. 17 is a sectional plan thereof taken on the line 17—17 of Fig. 15;

Fig. 18 is a sectional plan thereof taken on the line 18—18 of Fig. 15.

Fig. 19 is a cross-sectional elevation taken on the line 19—19 of Fig. 15;

Fig. 20 is a plan view illustrating the valve which controls the operation of the cut-off; and

Fig. 21 is a cross-sectional plan view taken on the line 20—20 of Fig. 14 illustrating the tempo valve.

Our invention will be best understood by a complete description of the mechanisms illustrated in the drawings.

Referring to the drawings and in detail, A designates the apertured tracker bar over which the perforated music sheet B is drawn from the usual music spool or roll C, by a take-up roll D, which is actuated through suitable gearing from a pneumatic motor E, which pneumatic motor can be connected to draw the music sheet forward over the tracker bar for playing or to reread the same on the music spool. The action F may be of any well known type, that shown in the patent granted to Thomas Danquard No. 766,601 August 2, 1904, being preferred.

The instrument illustrated is operated by suction or exhaust obtained from a pump G, which is provided with a suitable storer H, and which is driven by an electric motor I.

The action as illustrated is of the divided type, that is, the same is divided so that the bass section and treble section can be played independently of each other.

The pump is connected by a flexible pipe 30 to the cut-off hereinafter described, which cut-off is connected by pipes 31 and 32 to

- two expression controlling units J—J mounted on the right and left hand ends of the action, the right hand unit controlling the treble section of the action and the left hand unit controlling the bass section of the action. These expression units are the same, except they are rights and lefts. They are designed compactly so that they can be arranged in the positions illustrated.
- 5 The right hand or treble expression unit is detailed in the drawings and a description of the same will apply to the left hand unit with the understanding that the units are respectively rights and lefts.
- 10 The pipe 31 is connected to a passage block 33 which is secured to a valve seat block 34 forming the rear wall of a governing board 35, a passage 36 being cut through said board. The front of the box may be made of glass 37 if desired so that the operation of the valves can be watched. A sliding governor valve 38 is arranged in horizontal ways or guides 380 inside of said box. A governing pneumatic 39 is secured 20 to the left hand side of said governor box, and the movable leaf of this pneumatic is pulled to the left by a governor spring 40 attached thereto and adjustably connected to a bracket 41. The governor box 35 is 25 connected to the inside of said pneumatic by a passage 42 and the movable leaf of said pneumatic is connected to said governing valve by a link or rod 43. Also fitting in said ways is a sliding expression controlling valve 44, which valve can be moved 30 horizontally by a rod 45 extending out through the box and through the passage or duct board hereinafter described.
- 35 A passage 46 in said box connects to a nipple 47 and a pipe 48 is arranged to connect said nipple to the right hand or treble section of the action.
- 40 The expression controlling valve 44 is adjusted automatically by the mechanism hereinafter described. The right hand edge of the governor valve 38 co-operates with the left hand edge of the expression controlling valve 44, these edges being tapered as illustrated in Fig. 4 to obtain 45 sharp meeting edges on the valve so that the amount of air passing between the valves can be accurately controlled. The adjustment of the expression controlling valve determines the tension of the exhaust 50 which will be applied to the action at any instant, and the governing valve will maintain the suction at this adjustment so that the expression or dynamic effect will be the same whether one or many of the piano actions is or are called into operation at 55 the same time. For instance, suppose the expression controlling valve should be adjusted to the right. Then it will take a suction of greater tension, depending on 60 the amount of this adjustment, for the gov-

erning pneumatics to move the governing valve to the right up to the adjusted expression controlling valve, the governing pneumatic valve and spring functioning in a well-known manner to maintain the exhaust in the governing box at just the tension determined by the adjustment of the expression valve, no matter whether few or many notes are to play at the same time.

65 An adjustment of the expression controlling valve to the left will set the parts to apply a less tension to the action. In other words, the governing valve operates properly at all tensions within the limits of the device, the tension in the governing box 70 being determined by the adjustment of the expression controlling valve.

75 The arrangement illustrated is particularly desirable because the air control is obtained between the meeting edges of the two valves which can be accurately finished to close against each other so that a slight movement of either valve will give a large flow; and because both the governing valve and expression valve slide horizontally, 80 whereby the rush of air between the same will not cause either to flutter. Thus, a very accurate expression and governing control is obtained so that very delicate shadings of the expression may be brought out in the 85 playing.

90 The position of the expression controlling valve 44 is automatically adjusted by an expression pneumatic 49 which is secured on a passage or duct board 50. The expression pneumatic has an arm or bar 51 connected thereto, which arm or bar is connected to the rod 45 of the expression controlling valve by a metal piece 52 which is adjustably fitted on said rod between nuts or buttons 53 threaded thereon. A spring 54 is employed to give a lost motion in case the expression controlling valve is adjusted quickly to the left to strike on the governing valve. The expression pneumatic 49 is provided 95 with a spring 55 on its sides, which spring tends normally to expand the pneumatic and thus normally to adjust the expression controlling valve to the left for the lightest adjustment of the playing.

100 The expression pneumatic 49 is controlled by various valve units which may be arranged as follows:

105 A "forzando on" unit W is secured to the left of the passage board 50. This unit consists of a suitable block 56 in which is arranged a diaphragm 57 which is connected to a valve 58 which controls a passage extending into the board 50. The valve 58 is normally kept to its seat by a spring 59 and the extent to which this valve can open is adjusted by a screw 60, threaded into an arm or block 61 attached to said passage board 50. The valve block 56 is connected 110 by a pipe or tube 62 to the passage in the 115

block 33 so that suction is applied to the right of said diaphragm 56 as illustrated in Fig. 5. A small bleed is provided around said diaphragm. The chamber at the left of said diaphragm 57 is connected by suitable tubing 63 to a hole in the tracker bar, which may be designated as No. 6.

When a perforation in the music sheet uncovers this hole No. 6 the air admitted operates on the left of said diaphragm and moves the valve 58 against its spring and opens the same, thus connecting the suction to a passage 64 extending through said board 50 to the expression pneumatic 49. The flow when the valve is open is regulated by the adjustment of the screw 60. This flow tends to collapse the expression controlling pneumatic 49 and to move the expression controlling valve to the right so that a greater tension will be applied to the treble section of the action.

This adjusting movement of the expression pneumatic is controlled by the length of the perforation in the music sheet, for example, a short perforation *a* causes the expression pneumatic to close, say one-quarter way, as illustrated at *a'*, Fig. 13, a longer perforation *b* causes the expression pneumatic to close one-half way, as illustrated at position *b'*, and a still longer perforation *c* causes the expression pneumatic to close three-quarters way, as illustrated at *c'*. Thus, the length of the perforation in the music sheet will determine the extent of the collapsing movement of the expression pneumatic and any length of perforation may be employed to get any part of the complete collapsing movement, within the limits of the apparatus. This adjustment will take place very quickly as the screw 60 is adjusted to permit a rapid flow past the valve 58.

To allow the expression pneumatic to expand or to obtain the "forzando off" action, the following mechanism is provided:

A valve block 65 is secured to the left side of the duct board 50 and is connected to the block 33 by tube 66. The block 65 is provided with a diaphragm 67, the chamber at the left hand side of which is connected to tracker aperture 5 by tubing 68, a bleed being arranged around the diaphragm. This diaphragm is connected to operate a double valve 69 which controls a passage extending to a chamber at the left of a diaphragm valve 70, which controls a passage extending into the passage 64 connecting with the expression pneumatic. This valve 70 is kept normally closed by a spring 71. When a perforation *d* in the music sheet uncovers aperture 5 in the tracker bar, air will be admitted at the left of the diaphragm 67, which will move the valve 69 to the right, which will permit the exhaust to act on the left of the diaphragm valve 70, which will

open said valve and allow air to flow into the passage 64 which will allow the expression pneumatic 49 to expand quickly under the action of its spring 55. The chamber at the right of the diaphragm 67 is connected to another chamber in which is arranged another diaphragm valve 72 held normally closed by a spring 73. This valve controls an opening extending to a passage 74 in the block 50, which passage extends down and connects with the governor box 35. The valves 70 and 72 operate simultaneously so that as atmosphere is admitted into the expression pneumatic, atmosphere will also be admitted into the governor box which will allow the governing pneumatic 39 to expand rapidly under the action of its spring 40. Thus, when the expression pneumatic is allowed to expand rapidly the governing pneumatic is allowed to expand at the same time and the expression controlling valve and the governing valve 38 will move rapidly to the left, for the softest playing, or for another adjustment. The valves described to effect this "forzando off" may be arranged in a unit X. The "forzando on" and "forzando off" exhaust and supply to the expression controlling pneumatic are large enough so as to overcome the bleed into the expression controlling pneumatic and through the "crescendo on" hereinafter described.

To collapse the expression controlling pneumatic 49 slowly so as to obtain a crescendo effect, the following mechanism is provided.

A valve block 75 is arranged at the left of the units W and X as shown in Fig. 2. This valve block is provided with a so-called "locking" valve, which comprises a double valve 76 controlled by an upper diaphragm 77 and lower diaphragm 78, the chamber between the double valve and the lower diaphragm is connected by a pipe 79 to the exhaust passage in the block 33. The chamber in which the double valve 76 works is connected by a tube 82 to a nipple 83 which connects with the passage 64 in the duct board 50. An adjusting screw 84 is arranged in this nipple so that the flow through the same can be regulated. Another nipple 85 is connected to the passage 64 at the bottom of the board 50 and is provided with an adjusting screw 86 so that a small flow of atmosphere at all times is permitted into the passage 64. Bleeds are arranged around the diaphragms 77 and 78. When the aperture 4 in the tracker is uncovered by a perforation *e* in the music sheet, air is admitted under the lower diaphragm 78 which raises the double valve 76 and connects the passage 64 to the exhaust through the tube 82. The screw 84 is adjusted so as to permit a slightly larger flow than is permitted by the screw 86. Hence, the expres-

4

sion pneumatic now will be slowly collapsed under this action. It will be noticed that when the double valve 76 is lifted, it will remain in raised position as the exhaust will be admitted through the bleed into the chamber above the upper diaphragm 77. Therefore, the slow collapsing movement of the expression pneumatic will continue until a perforation *f* in the music sheet uncovers the aperture 3 in the tracker bar which will permit air to flow into this chamber and allow the valve 76 to drop. When the double valve 76 drops, the expression pneumatic will open slowly under the tension of its spring, air being admitted through the nipple 85. Thus, the expression pneumatic can be collapsed slowly or allowed to open slowly to obtain crescendo effects. This "crescendo on" and "crescendo off" mechanism is employed to move the expression controlling pneumatic up to the point determined by the stop pneumatic mechanism hereinafter described and not much in any beyond such point as the tension of the spring 55 will just about oppose the "crescendo on" adjustment beyond said point. The valve mechanism last described is conveniently arranged as a unit Y.

The stop device now to be described can be used to limit either the collapsing or expanding movement of the expression pneumatic. This apparatus consists of a pneumatic 87 arranged on top of the passage block 50. This pneumatic 87 is normally held open by a spring 88 and is provided with a hook 89 set in position to engage a prong 90 on the movable leaf of the expression pneumatic 49. A locking valve is arranged to control this stop pneumatic. This locking valve consists of a valve block 91 containing diaphragms 92 and 93 which operate a double valve 94, the chamber between the left hand diaphragm and the valve being connected to the exhaust passage in the block 33 by a tube 95. Bleeds are provided around the diaphragms. The chamber at the left of the left hand diaphragm 92 is connected by tubing 96 to tracker aperture 2 and the chamber at the right of the right hand diaphragm 93 is connected by tubing 97 to tracker aperture 1. When a perforation *g* in the music sheet uncovers hole No. 2 in the tracker bar, air is admitted to the chamber at the left of the left hand diaphragm 92 and the double valve 94 is moved to the right, which admits suction to the stop pneumatic closing it instantly. The stop pneumatic does not itself regulate the expression but it will in one operation prevent the expression pneumatic from closing beyond an intermediate point where the piano is being played medium loud or at mezzo-forte. On the other hand, if the stop pneumatic is called into operation after the expression pneumatic has been collapsed beyond this point, it will interfere with the opening of the expression pneumatic and will only allow the same to open to said point. In other words, the stop pneumatic will hold the expression pneumatic so that the regulations thereof all be on one side of said point.

When the double valve 94 is operated as last described it will remain in right hand position until a perforation *h* in the music sheet uncovers the aperture 1 in the tracker bar which will permit atmosphere to flow to the right of the right hand diaphragm 93 which will move the valve back to the normal position shown in Fig. 12. This valve apparatus may be conveniently arranged as a block *z*.

By using these locking valves with the "crescendo on" and "crescendo off" and with "stop pneumatic on" and "stop pneumatic off" these parts can be called in operation by an aperture of short length in the music sheet and held in operation until cancelled also by apertures of short length in the music so that long perforations in the music sheet are not needed. This permits the use of long perforations for "forzando on" without weakening the music sheet. It will be noted that "forzando on" and "forzando off", "crescendo on" and "crescendo off", and the "stop pneumatic" may be used in many combinations. For example, while the expression pneumatic is being slowly closed by a "crescendo on" "forzando off" may be added to bring out a single note or chord. If the "crescendo on" is called into operation after the "forzando on" has moved the expression controlling pneumatic past said stop point the "crescendo on" will substantially act to hold the "forzando on" at said point.

Thus, the expression or dynamics of the instrument can be automatically controlled from the music sheet. The expression pneumatic, its passage block and the various valve units before described may be manufactured and put together so as to form a single unit which can be made in quantities.

The expression units previously described have been particularly designed as an improvement on the mechanism shown and described in U. S. patent granted in the name of Edwin Welte, No. 1,225,905, dated May 15, 1917, entitled "Pressure controlling mechanism for automatic musical instruments." By placing these expression units on top of the action as illustrated they are rendered very accessible. Moreover, by this construction the action and expression units can be made and assembled by the action manufacturer and can be sent to the piano manufacturer who has simply to put the action in place in the piano and who thereupon does

not have to connect up the expression units.

The combined action cut-off and motor governor are attached to the bottom of the action and will now be described.

- 5 The same consists of a block 100 which is provided with a pipe elbow 101 to which the pipe 30 extending to the pump previously referred to is connected. The block is also provided with nipples 102 and 103 to which 10 the pipe 31 and 32 extending to the expression units and previously referred to are connected. The valve block 100 is provided with passages so that the elbow 101 connects with the nipples 102 and 103 through a valve 15 seat which is controlled by a valve 104, which is mounted on a diaphragm 105 contained in a supplemental block 106 secured to the bottom of the block 100, a suitable bleed being provided around said diaphragm. 20 The chamber under said diaphragm is connected, by a tube 107 to a valve seat 108 arranged on top of the action, co-operating with which seat is a small rotary valve 109 having an arm 110 connected as hereinafter 25 described. The rotary valve 109 is provided with a recess in which is arranged a pin extending from the seat to limit the motion of the valve and this recess controls an aperture extending from the tube 107 up through the 30 valve seat. When the valve is in the position shown in Fig. 20, the tube 107 is cut off from the atmosphere and the double valve 104 remains in its normal or lowest position shown in Fig. 19 so that the expression units 35 are connected with the suction of the pump. When the rotary valve is moved as illustrated by the arrow in Fig. 20, air is admitted to the tube 107 which, acting under the diaphragm 105, lifts the double valve 104 and 40 cuts off the expression units from the pump and thereby stops the playing of the instrument.

A passage 111 extends from the chamber in said valve block 100 in which the double 45 valve 104 operates into a governing pneumatic 112 which is normally opened by a spring 113 arranged between the movable leaf thereof and a bracket 114 as shown in Fig. 16. An extra fold of cloth V is used 50 in this pneumatic as a valve and is so positioned that when the pneumatic closes this cloth will cut off the passage 111, a screen covering the opening of this passage. The block 100 is also provided with a passage 55 115 extending into said governing pneumatic 112 and this passage is connected by a tube 116 to a tempo valve box 117 which is secured on top of the action. The tempo valve controls a passage connected by a 60 tube 118 to the pneumatic motor E. The tempo valve 119 is kept to its seat by a spring 120. A rod 121 is connected to said valve 119 and extends out through the tempo valve box and is connected to an adjusting 65 slide 122 which has a pointer co-operating

with a suitable scale by adjusting which the speed of the motor can be adjusted and hence the tempo of the playing can be regulated. The passage extending into the block 100 from the pipe 101 is connected by a 70 tube 123 to a replay-reroll-electric cut-out unit, which is mounted on top of the action at the left of the spool box as illustrated. This unit consists of a reroll pneumatic 124, the movable leaf of which has an arm 125 75 which fits on a rod 126 in position to engage an adjustable stop 127 thereon. This rod 126 is also connected to the shifting lever 128 of the gearing between the pneumatic motor E and the take-up roll and the music 80 spool, which gearing is of the usual form and need not be described. When said pneumatic 124 is collapsed, the rod 126 is shifted to the left, the motor is connected to the music spool for rewinding and the 85 suction or exhaust is cut off from the action as previously described. The unit also has another pneumatic 129, which has an arm 130 which is connected to a rod 131 extending into the spool box and having a handle 90 therein. This rod is connected by suitable adjustable fingers to the electric switch 132 which controls the operation of the electric motor I. When the rod is pushed to the left the motor is started in operation. When 95 the pneumatic 129 is collapsed the electric switch is thrown to cut the electric motor out of operation and thus stop the playing. This unit also has replay pneumatic 133, which has an arm 134 set in position to engage a stop 135 secured on the rod 126. When this pneumatic 133 is collapsed the 100 said rod 126 is moved to the right, the gearing between the pneumatic motor and the take-up roll is set in operative position and the rotary valve 109 is moved to cut out the 105 flow of air through the tube 107, whereby the action is connected to the suction or exhaust through the expression units and the instrument is started again in operation. 110 The reroll pneumatic 124, the cut-out pneumatic 129 and the replay pneumatic 133 are arranged on a suitable valve block 136 which is secured to the top of the action. This valve block has suitable valves which 115 are connected by tubes as indicated in dotted lines in Fig. 14 to suitable apertures in the tracker bar. It is not thought necessary to detail these valves at length as they are of ordinary construction. This valve block and these pneumatics may be made as a unit of manufacture conveniently attached at the point indicated. By this arrangement the music sheet will be rewound after playing and replayed if desired or 120 the instrument will be thrown out of operation after reroll, depending upon the cutting of the music sheet.

125 By the improvements previously described the operation of the reproducing piano is 130

6
greatly improved and the mechanism is organized and assembled so that it can be most expeditiously manufactured and placed in position in the piano.

5 The details and arrangements herein shown and described may be greatly varied by a skilled mechanic without departing from the scope of our invention as expressed in the claims.

10 Having thus fully described our invention, what we claim and desire to secure by Letters Patent is:—

15 1. An expression unit comprising a governing and expression controlling valve or valves, a governing pneumatic and spring, an expression controlling pneumatic and valves therefor, these parts being assembled and put together as a unit of manufacture capable of being mounted on the top of 20 a piano action.

25 2. An expression unit comprising a governing valve, pneumatic and spring, an independently operating expression controlling valve, an expression pneumatic, and valves for governing the operation of the expression pneumatic, these parts being assembled and put together as a unit of manufacture.

30 3. A divided player piano action having an expression unit for controlling the treble section of said action, and an expression unit for controlling the bass section of said units being mounted on top of said action so that said units can be connected before 35 the action is put into the piano.

4. A divided player piano action having an expression unit for controlling the treble section of said action, and an expression

unit for controlling the bass section of said action mounted on top of said action, and a 40 cut-off and governor unit mounted on the bottom of the action, so that said parts can be assembled with the action for installation in a piano.

5. A divided piano action having an expression unit for controlling the treble section thereof, an expression unit for controlling the bass section thereof, and a 45 reroll replay unit, all said units being secured to the top of said action, and a cut-off and 50 governing unit secured to the bottom of said action.

6. A divided piano action having an expression unit for the treble section thereof, an expression unit for the bass section thereof, and a reroll replay and electric switch unit, 55 all said units being secured to the top of said action, a cut-off and motor governor unit secured to the bottom of said action, whereby said units can be assembled on the 60 action before the same is installed in the piano.

7. A divided player piano action having an expression controlling unit for the bass section thereof, an expression controlling unit for the treble section thereof, and a reroll-replay-electric cut-out unit, all these 65 units being mounted on the top of said action so that they can be assembled before the action is installed in a piano.

70 In testimony whereof we have hereunto affixed our signatures.
